(57) **CLAIM**

The ornamental design for a bra as shown and described.

DESCRIPTION

FIG. 1 is a perspective view of a bra showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of area 9 shown in FIG. 2; and,

FIG. 10 is an enlarged view of area 10 shown in FIG. 4.

The dash dot broken lines illustrate the boundary of the enlarged views and form no part of the claimed design.
